UNITED STATES PATENT OFFICE.

CHARLES A. BOREIN, OF OAKLAND, CALIFORNIA.

WATER-HEATER.

No. 895,151.

Specification of Letters Patent.

Patented Aug. 4, 1908.

Application filed April 1, 1907. Serial No. 365,852.

To all whom it may concern:

Be it known that I, CHARLES A. BOREIN, a citizen of the United States, and residing at 33 Telegraph avenue, in the city of Oakland, 5 county of Alameda, and State of California, have invented certain new and useful Improvements in Water-Heaters; and I do hereby declare the following to be a full, clear, and exact description of the said invention, such as will enable others skilled in the art to which it most nearly appertains to make, use, and practice the same.

This invention relates to an improvement in gas burning water heaters, and particularly to a means for utilizing the waste heat from open burners on cook stoves.

The volume and velocity of a gas flame is such that it is not entirely absorbed by the contents of the cooking utensil subjected thereto. A considerable portion of it escapes from beneath the utensil and is lost by radiation. It is the practice to interpose a cast iron grid above the flame to support the utensil. This grid absorbs considerable heat which it radiates without economic results.

It is the object of this invention to conserve this wasted heat.

In the accomplishment of this object the invention consists broadly of a hollow grid interposed between the flame and the utensil and connected with a storage tank by suitable pipes in such a manner that water is circulated through the hollow grid absorbing that quantity of the total volume of the gas flame which would otherwise go to waste, and storing it within the storage tank. After the temperature of the water has been raised, within the grid the efficiency of the burner is increased by the regenerative action of the flame with the grid, that is to say, the volume of the heat stored within the grid prevents sudden chilling of the gas flame due to atmospheric disturbances, which are always present under the conditions applying to this invention. The velocity of a gas flame is so great that the ordinary flat surface of a cooking utensil will not absorb the whole volume of heat thrown off by a burner working at 50 normal capacity. Culinary conditions are such that a flame cannot be concentrated upon one spot; and if it is turned down sufficiently to diffuse the heat a sufficient aspiration is not present to give proper combustion 55 nor to overcome the cold space between the

top of the burner and the bottom of the utensil.

Practical demonstration has proven that the efficiency of the burner under ordinary conditions is not reduced appreciably by the attachment of this invention. Whereas a great economy is accomplished in the production of hot water which is a large item under conditions where this invention would be applicable.

In the drawing: Figure 1 is an isometrical perspective of a gas range having this invention applied thereto. Fig. 2 is an isometrical plan view from above of one of the hollow grids forming a part of this invention. Fig. 3 is a vertical cross section of the same with a diagrammatic representation of a gas burner thereunder.

In detail the construction consists of the hollow grid preferably circular in form with the hollow ring #2 cross connected diametrically by the hollow spokes #3 radiating from the hollow center #4. The rim being provided with the lugs #5, #6 for the pipe connections. The inlet pipe #7 communicates with the bottom of the storage tank #8. The outlet pipe #9 communicates with the top of the said storage tank. This tank may be connected to the city water main under full pressure or it may be used as a gravity tank as circumstances require. The inlet to the tank #8 being connected with the source of supply, at #11. One or all of the burners of a stove may be provided with these hollow grids which are preferably connected in series as shown. By this connection the water is progressively heated as it passes through each operative grid, *seriatim*. These grids may be constructed in any form or outline that occasion demands. The form shown cast as one integral piece with the chambers #10 cored therein being the preferred form. The upper surface is provided with the points #12 to elevate the utensil sufficiently to allow the flame to circulate freely all about the surface of the hollow grids.

By the exercise of some ingenuity, in the use of a cook stove supplied with this invention the varied temperature of the several grids can be taken advantage of in cooking. If a portion of the storage tank is inclosed within a compartment of the stove, such as #13, a double advantage results, the compartment acts as an excellent warming closet and the storage tank is thereby insu-

lated from a too rapid radiation of its heat units.

It is obvious that this invention is equally applicable to any gas, hydro-carbon or similar flame without departing from the spirit of the invention.

Having thus described this invention, what is claimed and desired to secure by Letters Patent is—

- 10 The combination with a gas stove provided with a warming oven or compartment, of a tank located in said oven, a plurality of circular grids each divided into a plurality of

annular chambers and a plurality of radial chambers connecting said annular chambers 15 and in communication therewith, means for heating said grids, pipes connecting said grids in series, means for supplying water to said grids, and a pipe leading from one of said grids to said tank.

In testimony whereof, I have hereunto set my hand this 11th day of March 1907.

CHARLES A. BOREIN.
